UNITED STATES PATENT OFFICE.

ELBERT H. CARROLL, OF WORCESTER, MASSACHUSETTS, ASSIGNOR TO
MORGAN CONSTRUCTION COMPANY, OF WORCESTER, MASSACHUSETTS,
A CORPORATION OF MASSACHUSETTS.

VALVE FOR SHEARING-MACHINES.

SPECIFICATION forming part of Letters Patent No. 787,324, dated April 11, 1905.

Original application filed July 8, 1902, Serial No. 114,781. Divided and this application filed August 3, 1903. Serial No. 168,101.

To all whom it may concern:

Be it known that I, ELBERT H. CARROLL, a citizen of the United States of America, residing at Worcester, in the county of Worcester, and State of Massachusetts, have invented certain new and useful Improvements in Valves for Shearing-Machines, as set forth in the annexed specification.

My invention relates to a valve for shearing-machines, and this application constitutes a divisional part of the application filed by me July 8, 1902, Serial No. 114,781.

In the accompanying drawings, Figure 1 is a view showing a side of a steam-shear for cutting billets, showing the application of my improved valve thereto. Fig. 2 is an enlarged sectional view of the cylinder and valve-body. Fig. 3 is a vertical section through the valve-body and valves, on an enlarged scale, on the line 3 3 of Fig. 2. Figs. 4 and 5 are broken sectional views on the same line, 4 4, of Fig. 6 on a much larger scale. Fig. 6 is an end view looking into the flanged ring forming a portion of the valve-body. Fig. 7 is a detail view of the gage for releasing the trip, and Fig. 8 is an enlarged detail view of the tripping mechanism.

Similar reference letters and figures refer to similar parts in the different views.

The object of my present invention is to accomplish the quick opening of the exhaust-port of the so-called "steam-flying" shears to cause the piston to respond instantly to the full expansive force of the head of live steam upon the piston, whereby to impart the required power to the shears necessary to sever the billet.

A further object is to keep the distance for steam travel between the valves at a minimum and also to maintain a minimum volume of steam in the connecting-ports.

Another object is to so construct and incase the valve mechanism that all parts thereof are kept hot and at a substantially uniform temperature.

With these objects in view my invention consists in certain novel features of construction

and combinations of parts, which will be hereinafter described, and pointed out in the claims.

Referring to the accompanying drawings, the cylinder 1 is stationed upon the machine-bed 2 in any approved manner and is shown on Fig. 1 at about an angle of forty-five degrees. The piston 3 is fitted within the cylinder and provided with a stem 3 at one end, and to the outer end the cross-head 4 is secured. The numeral 5 indicates the live-steam-supply pipe, and through this a continual head of steam is supplied to the outer or upper end of the cylinder through port 6. The valve-body 7 is conveniently secured to one side of the cylinder 1, as shown in Fig. 1. This valve-body may be variously constructed, but as shown has a general cylindrical form externally. Internally it is provided with several annular flanges 8, 9, and 10, which divide the valve-body into four chambers A, B, C, and D, respectively, in the order named, beginning at the outer or upper end. The inner edges of these flanges are in approximate alinement with one another and also in alinement with the openings 11 and 12, formed, respectively, in the opposite ends of the valve-body. Fitted to these inner circular edges are the two cylindrical bushings 13 and 14, which for convenience of construction are of slightly-different diameter and in the assemblage of parts necessitating their being inserted from opposite ends of the valve-body through openings 11 and 12, respectively. The bushings are turned to true cylinders inside and are provided with openings b, c, and d into the chambers B, C, and D, respectively. The opening 11 at the outer or upper end of the valve-body is closed by a head 15 and the opposite or lower end by a gland 16, this being bolted or otherwise secured in place and being provided with a cylindrical hub 17, which has a carefully-turned outer surface of somewhat less diameter than that of the inner surfaces of the bushings 13 and 14, with which surfaces it is concentric, so that an annular valve-chamber 18 is formed between said hollow annular hub

17 and the bushings 13 and 14. In this annular chamber the main valve 19 is fitted, it being hollow and cylindrical and of a length somewhat greater than the width of the three 5 chambers B, C, and D. This main valve is entirely open at its lower end and has a head 20 at its upper end, provided with orifices 21 21 therein. Valve 19 carries suitable packings 22 to make it steam-tight on its outer 10 surface, and the annular hub 17 may also have packings 22 to make the valve run steam-tight. The valve also has an annular recess 23 formed circumferentially about its surface, and a port 24 is made from this recess through 15 the valve. Stem 25 extends from the center of the main valve through the head 26 at the lower end of the gland, and on the projecting portion of the stem are mounted the cross-plates 27 and 28, the former of which is secured thereto and both of which are loosely mounted and capable of sliding upon guide-rods 29 29. These guide-rods have shoulders 30 30, against which the inner loose plate 28 is held by a spiral spring 31, the object of 25 which construction is to form a yielding buffer for the main valve when it reaches its extreme stroke in either direction. Within the hollow bore of the hub 17 of gland 16 there is an enlargement in the metal, which is counter-bored to form a cylindrical opening 32, and fitted to this and adapted to slide endwise therein is the hollow cylindrical pilot-valve 33, which is closed at its upper end and open 30 at its lower end and in communication with the interior of the hub 17 and chamber A of the valve-body. This pilot-valve 33 is reduced circumferentially, as at 34, whereby to form an annular recess, and this is adapted to bridge the two live-steam ports 35 and 36 when steam 40 is being admitted into the lower end of the cylinder to force the piston suddenly upward, as is illustrated in Figs. 3 and 4 of the drawings, to force the piston to the position illustrated in Fig. 2, the live steam being permitted, when the piston is in this position and by 45 the pilot-valve, to follow the course indicated by the arrow in Fig. 4 to impinge against the lower end of the main valve and force the latter into the position indicated in Figs. 3 and 4, so that steam may pass from a pipe 5' from 50 the upper end of the cylinder and thence through opening d, recess 24 in the outer wall of the main valve 19, through opening c into chamber C, which is in communication with 55 and supplies the lower end of the cylinder with steam. From the lower end of chamber 18 an exhaust-port 37 leads into the bore 32, in which the pilot-valve 33 slides, and out through this port 37 the steam exhausts when the pilot- 60 valve is moved outward in the direction indicated by the arrow, and when the pilot-valve is in the position shown in Fig. 5 the exhaust from the lower end of the cylinder escapes from chamber B through the opening b, which 65 has been opened by the movement of the main

valve, as shown in Fig. 5, thence into chamber A, and out through the discharge-orifice 38. (See Fig. 2.)

Of course it is understood that there is a constant pressure of steam at opposite ends 70 of the recessed portion 23 in the outer wall of the main valve; but the area of the inner or lower end is greater than the area of the opposite end, so that the valve will in that way be moved inward. This is what causes the 75 inward movement of the main valve when the exhaust-port 37 is opened. The area of the inner or lower end of the main valve 19 is still larger, and hence when live steam enters chamber 18 the valve is forced outward or upward, 80 due to the greater area exposed to the force of the steam. The valve will be moved inward with a sudden impulse until the port 37 is covered and the remaining steam in chamber 18 is compressed sufficiently to balance 85 the pressure in recess 24. The stroke of the main valve 19 after passing over the port 37 is controlled by exhausting the compressed steam from chamber 18 through a needle-valve 40, which can readily be adjusted, as it is obvious that the speed of the main piston 3^a is 90 entirely controlled by the stroke of the main valve 19. To regulate the rapidity with which steam is to enter chamber 18 from the lower end of the main valve, a needle-valve 41 is employed, it being set to the position necessary to admit the required amount of steam and at the speed desired.

From the foregoing it will be seen that the pipe 5 is connected with a constant steam-supply, the pipe 5 leading to the port 6 in the casting 1 of the cylinder, which port communicates with another pipe, 5', by means of a passage 5^a, formed by the upper end of the piston-head 3^a and the upper end of the cylinder. 100 Naturally if there is no counter-pressure in the cylinder 1 the pressure of the steam in the passage 5^a will force the piston-head downward to operate the shears. From the passage 5' the steam is led to the chamber D, as 105 shown in Fig. 2, whence the steam enters the recessed portion 23 of the main valve 19, thence into chamber C, whence it is led by the passage c' back to the cylinder 1 on the opposite side of the piston-head 3^a. An exhaust-passage 110 B' leads from the cylinder 1 to the chamber B in the valve-body 7, which chamber is normally closed by the main valve 19 to prevent the exhaust of steam from the cylinder. When the pilot-valve 33 is operated, however, 115 it uncovers the exhaust-passage 37 from the main-valve chamber 18, permitting the pressure of steam in the recess 23 of the main valve to move the same and uncover the chamber B to permit the exhaust of steam from the 120 lower end of cylinder 1 and simultaneously cut off the supply of steam to the cylinder by closing port c, leading to the chamber C in the valve-body. The movement of the pilot-valve 125 also shuts off the supply of steam to the 130

valve-chamber 18. With the opening of the chamber B the exhaust-passage B' of the cylinder is placed in communication with the exhaust-port 38 of the valve-body to permit the reduction of pressure in the cylinder and allow the pressure which is now practically locked in the passage 5^a to move the piston-head 3^a downward to operate the shears. The return of the pilot-valve to normal position reconnects the chamber 18 with the steam-supply through passage 36, reduced portion 34, passage 35, port 24, recess 23, port d, and chamber D, whereby the main valve is operated to close the exhaust-passage B' and connect chamber C with chamber D to admit steam below the piston-head 3^a to force the latter back into the position shown in Fig. 2.

The main valve is under the control of mechanism which will now be described.

A carriage 45^a is adjustably mounted on a suitably-supported rail 45^b adjacent the shears 46 46, the carriage having a gage 45 pivotally mounted intermediate its ends thereto. One end of the gage extends into the path of a moving billet suitably supported on rollers, as shown in Fig. 7. The gage is adjusted a predetermined distance from the shears and is operated by the engagement of the billet therewith, the movement of the gage operating to cause the movement of the piston through a train of mechanisms, and thus cause the shears to cut the billet. The gage is therefore swung upon its support 47, and one end thereof is normally retained in position across the path of movement of the billet by means of the spring 48, connecting the arm 75 of the gage, which arm is pivotally secured to the carriage at 47, and the bracket 76, rigidly secured to the carriage and projecting therefrom, as shown. A flexible connection 49 extends tautly between the free end of the arm 75 and the arm 51, suitably journaled in a bracket 80 on the valve-body 7. The engagement of the billet with the gage 45 moves the latter against the tension of the spring 48 and slackens the flexible connection 49, which permits a spring 50, weaker than is spring 48, to swing the arm 51, one end of the spring 50 being secured to the outer end of the arm 51 and the opposite end of the spring being adjustably connected with a suitable support.

The arm is provided at its inner end with a finger 52, adapted to engage the outer end of a pivotally-mounted trip 53, which trip is normally held against a lug 59, carried by a stop 57, by means of the spring 58, adjustably connected to the bracket 80 at its outer end. The stop 57 is preferably pivoted on the same support 57 with the trip 53, the lug 59 being located at one end of the stop, the opposite end of the stop being held, by means of an adjustable spring 54, in engagement with a shoulder 55 on the stem 56 of the pilot-valve to retain the latter in one position against the action of a spring 60. The pivotal support of

the trip will allow the finger 52 to sweep past its outer end should the finger ever drop to a position therebelow, owing to the movement imparted thereto by the spring 50. It will be seen that the retractile action of the spring 50 will cause the finger to smartly impinge against the trip 53, which through the lug 59 will raise the stop 57 and permit the stiff spring 60 to force the stem 56 of the pilot-valve outwardly or upwardly, the stem carrying a cushioning-cup 61, which engages the abutment 61^a, against which one end of the spring 60 bears. This is the initial action of the valve mechanism prior and preparatory to the downward movement of the piston 3^a in the operation of the shears, as heretofore described.

The cross-head 4, carried at the upper end of piston 2, is connected to the shears by means of the links 62 62. To cause the return or resetting of the pilot-valve to the position indicated in Figs. 3 and 4 of the drawings, an arm 63 is provided, which arm is fulcrumed intermediate its length, as at 64, the inner end of the arm being bifurcated, as at 65, to embrace or straddle and engage the valve-stem 56. The inner end 65 is caused to swing inwardly to engage a shoulder on the valve-stem 56 and force the valve back to its normal position against the action of the adjustable spring 74 by means of a rod 65', the lower end of which is connected with the outer end of the lever 63, while the upper end of the rod 65' is pivotally secured to a manually-actuated crank 66, capable of being set at different radial positions on a dial 67, provided with a series of apertures 68 68 for the purpose of adjusting the throw or arc of movement to be given the lever 63, the outer end of the crank 66 carrying a pin 81, receivable in any one of the apertures 68 68, the upper end of the rod 65' being secured to the outer end of the pin. The dial is secured on a rock-shaft 69, carried in a bracket 70. (See Fig. 2.) On the inner end of rock-shaft 69 an arm 71 is secured, which arm is connected by a link 72 to an arm 73, carried by the cross-head 4.

The operation may be briefly explained as follows: When the billet has reached the desired position to be cut, it strikes the gage 45, rocking it out of its normal position, causing the trip 53 to release the pilot-valve, as explained, the spring 60 operating to throw the pilot-valve outward or upward, opening the port 37 in chamber 18 and permitting the steam to exhaust therefrom into chamber A and thence out through the exhaust-port 38. The valve 19 descending uncovers opening b, allowing the exhaust-steam in the lower end of the cylinder 1 to escape and the piston-head 3^a, upon the upper end of which a full head of steam is being supplied, to rapidly descend and by so doing cause the operation of the shears. The descent of the piston also causes the rod 65' to raise the arm 63, forcing the rod 56 back to its normal position, the

trip automatically engaging shoulder 55 and locking the pilot-valve in its inner position owing to the tension of spring 54, as shown in Figs. 3 and 4, which movement of the pilot-valve establishes communication through ports 35 and 36 and the lower end of chamber 18, letting steam into the latter to force the main valve 19 upward to the position shown in Figs. 3 and 4, and also closing the exhaust-port B', leading into chamber A, and allows live steam to pass from pipe 5' into chamber D, thence through opening d into the circumferential recess 23 in the outer wall of main valve 19, thence out through the opening e in the bushing into chamber C, and from that chamber into the lower end of the cylinder to raise the piston.

What I claim as my invention, and desire to secure by Letters Patent, is—

1. In a shearing-machine, the combination with a piston and valve mechanism, the latter provided with a pilot-valve, of means for retaining the valve at one limit of its movement, mechanical means normally held under tension by the valve-retaining means and constantly tending to move the pilot-valve to its opposite limit of movement, a billet-operated tripping means for releasing the retaining means and means for subsequently engaging and returning the pilot-valve to its first position.

2. In a shearing-machine, the combination with a piston and cylinder, a valve mechanism, and a pilot-valve controlling the valve mechanism, of a rail, a carriage adjustably supported on the rail, and remaining stationary at the point to which it is adjusted, a gage pivotally mounted on the carriage, and normally lying in the path of the billets, a stop for retaining the pilot-valve in one position, means tending to move the valve to its opposite position, tripping means for releasing the valve, means connecting the gage and tripping mechanism and means for returning the valve to its first position.

3. In a shearing-machine, the combination with a valve mechanism, and a pilot-valve controlling the same, of a pivotally-mounted stop adapted to engage and retain the pilot-valve at one limit of its movement, adjustable tension means for bringing the stop into engagement with the valve, tension means constantly tending to move the valve to its opposite limit of movement and tripping mechanism for removing the stop from engagement with the valve.

4. In a shearing-machine, the combination with a valve mechanism, and a pilot-valve controlling the same, of a suitably-supported stud, a stop pivotally mounted on the stud, one end of the stop adapted to engage and retain the valve in one position, means constantly tending to move the valve to its opposite position, a lug projecting from the opposite end of the stop, a trip pivotally mount-

ed on the stud and abutting the lug, billet-actuated means for impinging against the trip to release the stop and subsequently-operated means for automatically returning the valve to normal position.

5. In a shearing mechanism operated by a piston, the combination with a valve mechanism and a pilot-valve controlling the same, of means for normally retaining the valve at one limit of its movement, means constantly tending to move the valve in the opposite direction, billet-operated tripping means for releasing the retaining means, a pivoted bifurcated lever engaging the pilot-valve, and means actuated by the piston for operating the lever to return the pilot-valve to normal position.

6. In a shearing-machine, the combination with a cylinder and piston, a valve mechanism and a pilot-valve, of means for normally retaining the pilot-valve at one limit of its movement, means constantly tending to actuate the pilot-valve to its opposite limit of movement, billet-operated tripping means for releasing the valve, a lever for returning the valve to normal position, adjustable tension means secured to the lever for adjusting and retaining the latter with relation to the valve to regulate the throw of the lever, and means operated by the piston for actuating the lever.

7. In a shearing-machine, the combination with a cylinder and piston, a valve mechanism and a pilot-valve, of means for normally retaining the pilot-valve at one limit of its movement, means constantly tending to move the valve to its opposite limit of movement, tripping means for releasing the retaining means, a lever for returning the valve to its normal position, a rotatable recessed plate, a rod connecting the lever to the plate, and link mechanism connecting the plate and piston to automatically operate the lever.

8. In a shearing-machine, the combination with a piston, of a pilot-valve normally retained against tension in one position, means for tripping the retaining means, a lever for returning the valve to normal position, an adjustable spring secured to the lever, means for adjusting the throw of the lever and means connecting the throw-adjusting means and the piston for automatically operating the lever.

9. In a shearing-machine, the combination with a valve mechanism and a pilot-valve controlling the same, of a shouldered stem secured to the pilot-valve, an abutment through which the stem is slidably received, means for normally retaining the valve at one limit of its movement, means for tripping the retaining means, a means constantly tending to move the valve to its opposite limit, a cushioning means carried by the valve-stem and engaging the abutment and means for returning the valve to normal position.

10. In a shearing-machine, the combination

with a piston, intermediate mechanism, and a pilot-valve controlling the same, of means for normally retaining the pilot-valve at one limit of its movement, billet-operated means for tripping the retaining means, means constantly tending to actuate the valve to its opposite limit of movement, a lever adapted to engage the valve, a suitably-journalized shaft, a rotatable perforated plate carried by the shaft, link-connected cranks carried by the shaft and piston, a rod connected at one end to the lever, a manually-operated crank pivotally secured to the plate, a pin carried by the outer end of the crank, one end of the pin receivable in any one of the perforations in the plate, the opposite end of the rod secured to the free end of the pin.

11. In a shearing-machine, the combination with a valve mechanism and a pilot-valve controlling the same, of a stop for retaining the valve at one limit of its movement, a lever for releasing the stop and valve, a gage-carriage located in approximate alinement with the shears, an arm pivotally mounted on the gage-carriage, a gage carried by the arm and extending into the path of a billet, a projecting bracket secured to the carriage, a spring connecting the bracket and arm for yieldingly retaining the gage in the path of the billet and means connecting the lever and arm for operating the former.

12. In a shearing-machine, the combination with a valve mechanism, and a pilot-valve controlling the same, the pilot-valve provided with a stem, of a stop for locking the pilot-valve at one limit of its movement, billet-operated means for releasing the valve, a suitably-supported lever, one end of which is bifurcated and loosely embraces the valve-stem intermediate its ends, the opposite end of the lever being perforated, a rod passing loosely through the perforation in the lever, an enlargement on the lower end of the rod, means

for adjusting the rod relative to the lever and means for operating the rod.

13. In a shearing-machine, the combination with a piston, valve mechanism controlling the movement of the piston and a pilot-valve controlling the valve mechanism, of a stop for engaging and retaining the valve-stem at one limit of movement, a billet-operated means for releasing the engagement of the stop and valve-stem, a suitably-pivoted lever, one end of which loosely engages the valve-stem, the opposite end of the lever being perforated, a rod passing loosely through the perforation, an enlargement on the rod for engaging the lever, a crank to which the rod is secured, a rotatable disk with which the crank is adjustably connected, and means for operating the disk.

14. The combination in a shearing-machine, with a pair of shears, a piston for operating one of the shears, a valve mechanism controlling the movement of the piston and a pilot-valve governing the valve mechanism, of means for retaining the pilot-valve in one position against its normal tendency, billet-operated means for causing the release of the valve, a suitably-pivoted lever, one end of which loosely engages the valve, a rod loosely connected with the opposite end of the lever, an oscillatory member, means connecting the member and the piston for operating the former, a crank-arm to which the rod is connected and means for adjustably connecting the crank-arm and the oscillatory member for regulating the throw of the lever.

In testimony whereof I have hereunto signed my name in the presence of two subscribing witnesses.
